We claim the ornamental design for a lid for container, as shown and described.

DESCRIPTION

FIG. 1 is a perspective view of a lid for container, showing our new design in a first configuration;

FIG. 2 is a front view thereof;

FIG. 3 is a left side view thereof;

FIG. 4 is a rear view thereof;

FIG. 5 is a right side view thereof;

FIG. 6 is a top plan view thereof;

FIG. 7 is a bottom plan view thereof;

FIG. 8 is another perspective view thereof, shown in a position of use with an exemplary container;

FIG. 9 is a perspective view thereof, shown in a second configuration;

FIG. 10 is a front view thereof;

FIG. 11 is a left side view thereof;

FIG. 12 is a rear view thereof;

FIG. 13 is a right side view thereof;

FIG. 14 is a top plan view thereof;

FIG. 15 is a bottom plan view thereof; and,

FIG. 16 is another perspective view thereof, shown in a position of use with an exemplary container.

The broken lines are shown for the purpose of illustrating both parts of the lid for container as well as environmental subject matter of an exemplary container. None of the broken lines form part of the claim.
